(57) **CLAIM**

The ornamental design for an apparatus for wrist and catheter stabilization, as shown and described.

DESCRIPTION

FIG. 1 is a left side perspective view of an apparatus for wrist and catheter stabilization;

FIG. 2 is a right side perspective view of the apparatus for wrist and catheter stabilization of FIG. 1;

FIG. 3 is a left side elevation view of the apparatus for wrist and catheter stabilization of FIG. 1;

FIG. 4 is a right side elevation view of the apparatus for wrist and catheter stabilization of FIG. 1;

FIG. 5 is a rear end elevation view of the apparatus for wrist and catheter stabilization of FIG. 1;

FIG. 6 is a front end elevation view of the apparatus for wrist and catheter stabilization of FIG. 1;

FIG. 7 is a bottom view of the apparatus for wrist and catheter stabilization of FIG. 1; and,

FIG. 8 is a top view of the apparatus for wrist and catheter stabilization of FIG. 1.

Broken lines in the drawings illustrate portions of the apparatus for wrist and catheter stabilization that form no part of the claimed design.

1 Claim, 8 Drawing Sheets
